UNITED STATES PATENT OFFICE.

ROYAL REUBEN MILLER, OF CHICAGO, ILLINOIS, ASSIGNOR TO ELECTRIC ROTARY MACHINE CO., OF CHICAGO, ILLINOIS, A CORPORATION OF ILLINOIS.

SURFACE-WORKING MACHINE.

1,299,989.

Specification of Letters Patent. Patented Apr. 8, 1919.

Application filed June 12, 1916. Serial No. 103,273.

To all whom it may concern:

Be it known that I, ROYAL REUBEN MILLER, a citizen of the United States of America, and a resident of Chicago, county 5 of Cook, and State of Illinois, have invented certain new and useful Improvements in Surface-Working Machines, of which the following is a specification.

The main objects of this invention are to 10 provide an improved form of surface working machine of the rotary type; to provide improved means whereby the pressure of the operating tool (of the device) on the surface operated upon may be varied within 15 wide limits by causing more or less of the weight of the machine to be borne by either such tool or the supporting frame of the machine; and to provide a cleaning machine in which the cleaning apparatus may 20 be yieldingly adjusted with respect to the surface to which it is applied.

An illustrative embodiment of this invention is shown in the accompanying drawings, in which—

25 Figure 1 is a side elevation of the cleaning machine equipped with carborundum stones for cleaning devices.

Fig. 2 is a top plan of the same with part of the housing removed.

30 Fig. 3 is a side elevation of the cleaning machine equipped with a scrubbing brush as the cleaning medium.

Fig. 4 is a top plan of the same.

Fig. 5 is a detail showing the yieldingly 35 adjustable means.

The general type of cleaning machine is disclosed and a detailed description of how the electric driving motor is mounted within the housing and is connected to the cleaning device may be found in my copending application, Serial No. 103,274 filed of even date herewith.

In the construction shown in the drawings the cleaning machine comprises a housing 1 within which is mounted an electric motor. 45 A circular plate 2 driven by such electric motor is journaled on the under side of the housing and is adapted to have various working tools such as carborundum stones 50 3 or a scrubbing brush 4 attached thereto.

Means are provided for adjustably supporting the housing containing the electric motor whereby the amount of pressure borne on the cleaning apparatus may be varied at will, and comprises a framework 55

adapted to surround the housing 1 and provided with suitable supports such as the casters 6 or rollers 7.

Yieldingly adjustable connection between the frame 5 and housing 1 is provided by 60 means of a yoke 8 fulcrumed at 9 on up-standing lugs 10 of frame 5, the branches of said yoke embracing the housing and having pivotal connection therewith by means of studs 11 mounted on a band or hoop 12 65 which surrounds and grips the housing. The hoop 12 may be clamped about the casting at various heights for the purpose of regulating the distance between the disk 2 and the surface operated upon. This 70 method of pivotally mounting the machine on pivots having an axis transverse to the direction of travel of the machine permits a rocking movement whereby the working tool will bear pivotally upon a surface 75 which has depressions or the like therein.

The shank 13 of said yoke is mounted in a vertical guideway 14 on frame 5 and yielding adjustment thereof is secured by means of a compression spring 15 and hand wheel 80 16 having a threaded stem 17 and foot 18 for bearing down on said shank.

In the operation of the device, any amount of pressure from a light contact to the full weight of motor and housing may be put 85 upon the cleaning device by turning the hand wheel 16 and actuating the shank 13 of yoke 8.

This wide range of adjustment is very desirable when various kinds of cleaning devices are used. When carborundum stones are being used on the cleaner, it is usually desirable to have a considerable weight bearing down upon them. Such weight, however, would be entirely unsatisfactory 95 when a scrubbing brush such as shown in Fig. 3 is used in scrubbing floors and rugs. If the amount of weight necessary for proper use of the carborundum stones were placed upon this brush, the bristles would 100 be bent and broken and would not give efficient and satisfactory service. The framework shown in Fig. 4 is slightly modified so that rollers 7 may be used when the machine is operated on rugs and the like, as casters 105 such as shown in Fig. 1 bear down deeply into the surface of such rug and make the machine very hard to move from one position to another.

Although but one specific embodiment of 110

this invention is herein shown and described, it will be understood that the construction may be altered and details omitted without departing from the spirit of this invention 5 as defined by the following claims.

I claim:

1. A device of the class described comprising driving means, a surface working apparatus supported from and actuated by said driving means, a supporting frame, a yoke having the branches thereof fulcrumed on said frame, said driving means being supported on and between said branches, a guideway mounted on said frame adapted 10 to receive the shank of said yoke, and an adjustable yielding means mounted on said guideway for controlling the position of said yoke shank.
2. A device of the class described comprising driving means, a surface working apparatus supported from and actuated by said driving means, a supporting frame, a yoke having the branches thereof fulcrumed on said frame, said driving means being supported on and between said branches, a 15
- 20
- 25

guideway mounted on said frame adapted to receive the shank of said yoke, a compression spring slidably mounted on said guideway in position to bear against said shank, and means for adjusting said spring along 30 said guideway.

3. A device of the class described comprising driving means, a surface working apparatus supported from and actuated by said driving means, a supporting frame, a yoke having the branches thereof fulcrumed on said frame, said driving means being supported on and between said branches, a guideway mounted on said frame adapted to receive the shank of said yoke, a compression spring slidably mounted on said guideway in position to have one end thereof bear 35 against said shank, a stem having threaded engagement with said guideway, a foot on said stem for bearing against the other end 40 of said spring, and a handwheel on said stem.

Signed at Chicago this 26th day of April, 1916.

ROYAL REUBEN MILLER.
